J. H. MILLER

DISPENSING CAN

Filed April 9, 1925

INVENTOR
Joseph H. Miller
BY
Charles B. Mann, Jr.
ATTORNEY

UNITED STATES PATENT OFFICE.

JOSEPH H. MILLER, OF HARRISBURG, TEXAS.

DISPENSING CAN.

Application filed April 9, 1925. Serial No. 21,745.

To all whom it may concern:

Be it known that I, JOSEPH H. MILLER, a citizen of the United States, residing at Harrisburg, in the county of Harris and 5 State of Texas, have invented certain new and useful Improvements in Dispensing Cans, of which the following is a specification.

This invention relates to improvements in 10 dispensing cans and is particularly directed to a can having a discharge-nozzle or spout through which the contents may be discharged.

While a can embodying the features of 15 the present invention may be utilized for dispensing various substances, I have particularly designed it for the purpose of economically and effectively distributing liquid dressing on traveling machinery belts.

20 Belt dressing should be dispensed from a can which when not in use may be closed against the entrance of dirt or dust and kept sufficiently tight to prevent evaporation of some of its important ingredients and 25 the can should be provided with a nozzle structure that will permit the dressing to flow therefrom in a way that will facilitate the spreading thereof on the belt, and the closure for the nozzle should be arranged 30 for ready attachment to or removal from the nozzle.

The object therefore of the present invention is to provide an improved dispensing can having a nozzle of novel construction.

35 The invention is illustrated in the accompanying drawing, wherein,—

Fig. 1. shows the complete can in side elevation.

Fig. 2. illustrates the upper portion of 40 the can and the nozzle,—the latter being tilted as in the act of connecting the same to the can.

Fig. 3. shows a portion of the can and the 45 attached nozzle in longitudinal section,—the nozzle cap being in the detached position.

Fig. 4. illustrates the discharge-end of the nozzle as viewed on the line 4—4 of Fig. 3.

Fig. 5. shows a cross-sectional detail as taken on the line 5—5 of Fig. 3, and

50 Fig. 6. illustrates another cross-sectional detail as viewed on the line 6—6 of Fig. 3.

Referring to the structure shown in the drawing the numeral 10, designates the cylindric body of the container, which in this 55 instance is presumed to be a sheet metal can.

The head-end 11 of this can has a breast 12, with a central nipple 13 and this nipple is exteriorly threaded at 14 with coarse threads and has a central opening 15 therein. A flat ledge 16 is formed on the nipple about 60 the opening 15 for a purpose that will presently be explained.

With the container or can, I provide a spout or nozzle 17 containing novel features.

This nozzle 17 is slightly tapered, being 65 larger at its base or attaching-end than at its discharge-end and at the larger end it is internally screw-threaded so as to fit over and screw onto the nipple 13.

A cross-wise plate or partition 18, is provided on the interior of the nozzle near its attaching end and this partition has a series of perforations 19 and also a central perforation 20. The partition is so spaced from the end of the nozzle that when the latter 70 is screwed onto the nipple said plate or partition will seat on a washer or gasket 21, that is interposed between it and the ledge 16 of the nipple whereby to effect a tight joint about the nipple-opening 15. 80

At the smaller discharge-end 22, of the nozzle I provide a cross-bar 23 on the interior of the said nozzle and this cross-bar has a central opening 24 which is in axial alinement with the central opening or perforation 20 in the partition 18 whereby said two perforations 20 and 24 will serve as 85 guide-openings for a stem 25 that extends longitudinally through the nozzle.

The stem 25 is preferably formed of wire 90 and has a flat or elongated loop 26 formed at that end which projects from the larger end of the nozzle after passing through the partition plate 18.

Particular attention is directed to the flat 95 or elongated loop 26 because it will be noted that a greater portion of the length of said loop projects at one side of the stem 25 than the portion of said loop that extends from the opposite side of said stem. In other words, this loop is so formed with respect to the stem 25 that the distance from one side 27 on the loop to the axis of the stem is greater than the distance from the opposite side 28 to said stem-axis. 100

The purpose in thus forming the loop with one side broader than the other is, that it prevents entire detachment of the nozzle from the can in a straight-away direction 110 and makes it necessary to turn the loop in

a precise position to effect such detachment thereby preventing accidental detachment and loss of the nozzle.

5 By turning the stem until the short side 28 of the loop can be swung out through the nipple-opening 15, a ready detachment may be effected, as shown in Fig. 2 of the drawing.

10 Between the partition plate 18 and the bridge or cross-bar 23, I provide the stem 25 with a cross-plate 29, having flat sides 30 to provide passages 31 in the nozzle for the inlet of air and the outlet of the fluid or dressing during the pouring operation.

15 When the stem 25 is drawn out the round edges of the cross-plate 29 will bind in the tapered passage of the nozzle and thus hold the stem in the outward or projected position.

20 The extreme outer end of the stem 25, is permanently attached to the under side of a flanged cap 32. This cap is slightly tapered so it may fit over and seal the smaller end of the nozzle when the stem is pushed inwardly but as the cap is attached to the stem when it is drawn outwardly to uncover the nozzle-end the stem will be pulled out with it until the plate 29 wedges in the nozzle and holds the cap in the uncovered position and well out of the path of the pouring liquid.

25 As the cap is permanently attached to the stem and the stem is permanently secured in the nozzle, loss of the cap will be prevented and the reseating of the cap on the nozzle is simply a matter of pushing the cap and stem inwardly into seating position.

Having described my invention, I claim,—

30 1. In a dispensing can the combination with a cylindric body having a projection at one end thereof, of a tapered nozzle to connect with said body-projection at its larger end, a stem extending all the way through the nozzle and passing through the 45 projection on the body, means in the nozzle for guiding the stem therein and a cap attached to the outer end of the stem and shaped to cover the smaller end of the nozzle.

50 2. In a dispensing can the combination with a cylindric body having a projection at one end thereof said projection being provided with an opening, of a tapered nozzle detachably connected to the projection,—said nozzle having cross-wise guide-means

therein, a stem extending all the way through the nozzle and guided by said guide-means therein said stem having its inner end passing through said projection-opening and being enlarged at said inner end and a cap attached to the outer end of the stem and shaped to cover the smaller end of the nozzle.

3. A nozzle for a dispensing can comprising a tapered tube interiorly threaded at its larger end and having a partition plate extending crosswise thereof near said larger end said tube also having a cross-wise guide-bar near its smaller end, a stem extending into the tube and passing through the guide-bar and partition-plate, a cap attached to the outer end of the stem for closing the smaller end of the tube and means on the stem and within the tube for limiting the outward movement of the stem and for holding the stem and cap in the outwardly-extended position.

4. A nozzle for a dispensing can comprising a tapered tube interiorly threaded at its larger end and having a partition plate extending crosswise thereof near said larger end said tube also having a cross-wise guide-bar near its smaller end, a stem extending into the tube and passing through the guide-bar and partition-plate, a cap attached to the outer end of the stem for closing the smaller end of the tube and a plate attached to the stem between the partition-plate and the guide-bar said plate on the stem having edges that frictionally engage the interior of the tapered tube as the stem and cap are moved outwardly to hold the latter in the unseated position in front of the tube.

5. In a dispensing can the combination with a cylindric body having a projection at one end thereof said projection being provided with an opening, of a tapered nozzle 95 detachably connected to the projection,—said nozzle having cross-wise guide-means therein, a stem extending all the way through the nozzle and guided by said guide-means therein said stem having its inner end passing through said projection-opening and the inner end of the stem having a loop formed thereon with one side of the said loop off-set from the stem a greater distance than the other side of said loop.

100 In testimony whereof I affix my signature.

JOSEPH H. MILLER.
